UNITED STATES PATENT OFFICE

BJARNE H. SCHIELDROP, OF PITTSBURGH, PENNSYLVANIA, ASSIGNOR TO BLAW KNOX COMPANY, OF PITTSBURGH, PENNSYLVANIA, A CORPORATION OF NEW JERSEY

METHOD AND APPARATUS FOR PROJECTING LOOSE MATERIAL

Application filed September 29, 1927. Serial No. 222,740.

My invention relates to methods and apparatus for projecting loose or plastic material and particularly to methods and apparatus for applying material to furnace linings, although its use is not limited in this respect.

In repairing small areas in furnace linings, it is desirable that the repair material be added while the furnace is in a heated condition. This condition prevents the direct application of the repair material to the furnace walls by hand.

Machinery has heretofore been provided for injecting or throwing the repair material into the heated furnace. Provision has been made in such machines for directing the stream of material into different parts of the furnace.

For throwing the material, it has been fed onto a belt travelling at a high rate of speed and discharged from the belt by its own inertia as the belt passes around a pulley. Such a machine is shown and described in my Patent No. 1,576,366, dated March 9, 1926.

In that machine the material is fed from a bin into a groove in a pulley. A projecting belt engages the outer face of the pulley and encloses the groove. The material is thrown from the face of the groove, or by an auxiliary belt, onto the face of the driving belt.

In such constructions where the material is thrown from the face of the groove onto the projecting belt, the surface of the groove becomes worn and smooth, thereby permitting the material to slip relative to the surface of the groove. Such slippage reduces the velocity of the material when fed upon the projecting belt and, consequently, the efficiency of the machine.

To increase the frictional engagement between the face of the groove and the material, I add corrugations. The faces of the corrugations may be protected from wear by providing removable facing strips such as bolts or rods extending through the pulley. By utilizing corrugations and protecting strips, it materially increases the efficiency of the projecting machine.

For controlling the direction of the discharged material, the grooved pulley, belt and driving machinery are mounted on a turn-table, the position of which is controlled

by a handle. By raising or lowering the position of the handle, the inclination of the discharged material to the horizontal is controlled. The same handle is made to control a gate for shutting off the supply of material to the pulley by a twisting motion. This construction eliminates separate control rods for a bin gate and concentrates all the control mechanism in one operating handle.

In order to increase the range of applicability of the machine, I provide a curved spoon carried by the projecting machine and insertable through a furnace opening into the path of the projected material. Upon engagement with the spoon the course of the projected material is deflected, and it is directed into heretofore inaccessible places. By the use of a spoon I am able to repair the front walls of a furnace, which walls have heretofore been inaccessible.

The accompanying drawings illustrate the present preferred embodiment of the invention, in which:

Fig. 1 is a view partially in elevation and partially in section of the projecting machine,

Fig. 2 is a plan view thereof with the storage bin removed,

Fig. 3 is a view partially in elevation and partially in section of a material-handling pulley,

Fig. 4 is a sectional view of a bin gate,

Fig. 5 is a perspective view of a spoon for directing the discharged material,

Fig. 6 is a plan view of the details of the operating handle, and

Fig. 7 is an elevational view thereof.

Referring to Fig. 1, a projecting or throwing machine 1 comprises a pulley 2 that receives material such as dolomite, for repairing a furnace lining, from a bin 4 and transfers it to a projecting belt 5. The pulley 2 and belt 5 are mounted on a turn-table 6 carried by a framework 7 that also supports the bin 4. The framework 7 is mounted on a truck mechanism 8 that travels along a track 9.

Referring to Fig. 2, a motor 10 and reducing gears 11 are provided for actuating the truck mechanism 8.

For controlling the angular position of the projecting belt 5 on the frame 7, I provide a handle 12. By swinging the handle 12 to the right or left, and thereby turning the pulley 2 and belt 5 around the turn-table 6 as a unit, the horizontal direction of the discharged material may be varied by approximately 90°. It is to be understood that the amount of such angular movement 10 may be varied as desired. The handle 12 is provided with a telescoping section 13, connected to a gate 14, shown in detail in Fig. 4; and a section 15 connected between a swivel coupling 15^a and a bell crank 16 seated in a bearing 16^a secured to the frame of the machine for controlling the release of the discharged material as hereinafter explained. The details of the handle 12 and bell crank 16 are shown in Figs. 6 and 7.

20 Pulley 2 is disposed below and at one side of the gate 14 so that when the gate 14 is opened the material is delivered from the bin 4 through a chute 17 into a groove 18 therein. The bottom of the groove 18 is provided with corrugations 19 for engaging the material and imparting a tangential movement thereto. The outer surfaces of the corrugations, which are exposed to the greatest amount of wear are protected by removable rods or bolts 20 that extend through the pulley 2 across the groove 18. The rods or bolts 20 may be secured in place by any well-known fastening means, one of which is here illustrated as cotter pins 21. The rods or bolts 25 20 may be readily replaced. The pulley 2 is directly driven from a motor 22.

A stationary pulley 24 is mounted above the pulley 2 and at one side of the chute 17. A second stationary pulley 25 is mounted below the axis of and at one side of the pulley 2. A third pulley 26 is mounted at one end of the rocker arm 16. The three pulleys, 24, 25 and 26 are disposed in substantially triangular relation. The projecting belt 5 passes over the outer surfaces of the pulleys 24, 25 and 26 and engages a flange 27 in the outer surface of the pulley 2. The arc of engagement between the belt 5 and pulley 2 is on the inner side of the pulley 2, relative to the triangle defined by pulleys 24, 25 and 26. The direction of movement of the belt 5 is determined by the direction of rotation of the pulley 2.

55 The pulley 26 is disposed adjacent to an opening 28 in a shield 29. By raising or lowering the handle 12 the position of the pulley 26 relative to the opening 28 is varied by movement of the bell crank 16. Movement of the pulley 26 varies the inclination of the tangential portion of the belt 5 between the pulley 2 and pulley 26, thereby varying the elevation of the projected material. Since the direction and inclination 60 65 of the projected material may be controlled,

it is possible to reach substantially the entire side and back walls of a furnace.

Referring to Figs. 2 and 5, for reaching the front walls 30 of a furnace, I provide a curved spoon 31 supported by a handle 32. 70 The handle 32 is carried by a projecting angle iron 33 mounted on frame 7. By inserting the spoon 31 through a furnace opening and into the trajectory of the discharged repair material 34, it is possible to deflect 75 the material and cause it to engage the furnace walls adjacent to the opening. Such walls have heretofore been inaccessible to the material discharged by the projecting machine.

80 Referring to Fig. 4 for controlling the supply of material from the bin 4 to the pulley 2, the gate 14 is of arcuate contour and is carried by an arm 36 mounted on a shaft 37. The shaft 37 terminates in a coupling 38 connecting to the telescoping portion 13 of the handle 12.

85 In the operation of the projecting machine the operator grasps the handle 12 and turns the motor 22, projecting belt 5, pulley 2 and shield 29 about the turn table 6 until the opening 28 faces in the desired direction. The turning movement is transmitted through the handle 12, the swivel coupling 15^a, the handle section 15 and the bell crank 16 to the 90 bearing 16^a. The handle 12 is then depressed or elevated for controlling the inclination of the portion of the belt between the pulleys 2 and 26 by turning the bell crank 16 in order to give the proper inclination to the discharged material. During the depression or 95 elevation of the handle 12, the swivel coupling 15^a, the telescoping section 13, and the coupling 38 adjust themselves to allow for the angular movement of the parts about the 100 several pivots constituted by the bearing 16^a, the swivel coupling 15^a and the coupling 38. The handle 12 is then turned to open the gate 14 by turning the shaft 37. The repair material, such as dolomite and the like, is then 110 fed from the bin 4 into the groove 18 in the pulley 2. The material engages the corrugations 19 and bolts or rods 20 and is given a tangential impulse into engagement with the belt 5 which closes the groove 18. It is to be 115 understood that the arc of engagement between the belt 5 and the pulley 2 is made sufficiently long to insure that all of the material given a tangential impulse by frictional surfaces of the groove 18 shall engage the belt 5. 120 The material having engaged the belt 5, adheres thereto by reason of centrifugal force during its travel around the arc of engagement between the pulley 2 and belt 5. When the tangential portion of the belt 5 is reached 125 the material travels forward in a straight line. At the point where the belt 5 departs from a tangent and curves around the pulley 26, its inertia is such as to project it through the opening 28 and into engagement with the 130

furnace wall or the like opposite thereto. If it is desired to deflect the trajectory of the material 34, the spoon 31 is inserted into the furnace. In this manner the entire inner lining of the furnace may be reached.

5 While I have described my invention as applicable to the re-lining of furnaces, it is to be understood that its use is not so limited and that it can be applied to the handling of material other than furnace linings and for projecting material into spaces other than furnaces. Examples of other uses of such machines are for loading of box cars or the piling of stacks of loose material in places 10 where it is impracticable to place a belt or other kind of conveyor.

15 While I have shown and described a preferred embodiment of my invention it will be understood that changes may be made in the details of construction and that it may be otherwise practiced without departing from the spirit of the invention or scope of the appended claims.

I claim:

20 1. In a projecting device, a pulley having a circumferential groove therein and frictional means comprising corrugations disposed at the bottom of the groove.

25 2. In a projecting device, a pulley having a circumferential groove therein and frictional means comprising removable members extending transversely of the groove.

30 3. In a projecting device, a pulley having a peripheral groove therein and frictional means comprising corrugations and removable metallic wearing members cooperating with the surfaces of the corrugations.

35 4. Apparatus for projecting loose material comprising a pulley having a peripheral groove, frictional means disposed at the base of the groove, a belt having its outer surface in engagement with the periphery of said pulley and spanning said groove, said belt being bent around said pulley to engage a substantial arc of its periphery, means for driving said last mentioned belt and rotating said pulley, and means for feeding material into said groove and into engagement with the frictional means at the upper side of said 45 pulley, substantially as described.

50 5. Apparatus for projecting loose material, comprising a pulley mounted to rotate upon a horizontal axis and having a peripheral groove terminating in frictional surfaces, a belt having its outer surface in engagement with the periphery of said pulley and spanning said groove, said belt being bent around said pulley to engage a substantial arc of its periphery, a support for said pulley and belt 55 rotatable on a vertical axis and means for adjusting the discharge end of said belt vertically, substantially as described.

60 6. Apparatus for projecting loose material comprising a pulley mounted to rotate upon a horizontal axis and having a peripheral 65

groove terminating in friction means, means for controlling the supply of material to the groove, a belt having its outer surface in engagement with the periphery of said pulley and spanning said groove for conveying material received from the pulley, said belt being bent around said pulley to engage a substantial arc of its periphery, a support for said pulley and belt rotatable on a vertical axis, and means for adjusting the discharge 70 end of said belt vertically and horizontally and for controlling the supply means.

75 7. In the method of lining the inner walls of a furnace adjacent to a door, the steps consisting in throwing a stream of material through the open door and deflecting the stream of material from its direction of movement while passing through the door into engagement with an inner wall of the furnace adjacent to the door.

80 8. In the method of lining the inner walls of a furnace adjacent to a door, the steps consisting in throwing a stream of material through the open door and deflecting the stream of material from its direction of movement while passing through the door into engagement with an inner wall of the furnace 85 inaccessible to said stream of material while following a trajectory in which it passes through the open door.

90 In testimony whereof I have hereunto set my hand.

BJARNE H. SCHIELDROP.
